LIGHTING PROJECTILE

Edgar William Brandt, Paris, France, assignor to
 Sageb, Société Anonyme de Gestion et d'exploitation de brevets, Fribourg, Switzerland, a corporation of Switzerland

Application January 21, 1941, Serial No. 375,334
 In France January 12, 1940

5 Claims. (Cl. 102—35)

The object of the present invention is a lighting projectile more particularly intended to be fired from smooth bore mortars.

It has been designed in such a manner as to enable it to carry to far greater ranges than the usual projectiles. It is provided with a device which makes it possible, prior to firing, to regulate the period of time at the expiration of which ejection will occur, said period commencing at the time the shot is fired.

The projectile in question is of the type comprising a torpedo shaped body in which are enclosed: the flare slab, a suspension parachute and an ejecting charge; the body being provided, at the rear, with a radially perforated tubular tail intended to accommodate a propelling cartridge.

It is characterised, in particular, by the fact that said tail is rotationally mounted in the base of the projectile and that it comprises a unit for igniting the ejecting charge, said unit, according to the angular setting given to the tail, being capable of co-operating with either of several combined igniting units, the delay actions of which are different, positioned within an axial rod connecting the movable tail with the ejecting charge, the front end of said rod being provided with a plate which bears against a shoulder in the body of the projectile and serves as a rear support for the flare slab.

The igniting unit housed within the rotating tail may be, for instance, a small rod intended to be driven by the deflagration of the propelling cartridge against a primer cap of the delay action compound intended to ignite the ejection charge.

According to another peculiarity of the invention, the cartridge-carrying tail which is provided, at the rear, with stabilising fins is equipped, in front of the latter, with a flange directed rearwards which serves as a retainer for cartridge bags containing additional propelling charges which come into engagement on the one hand with said flange and, on the other hand, with the suitably incurvated front edge of the fins.

Other advantages and peculiarities of the present invention will appear in the following description.

In the attached drawing given merely as an example:

Figure 1 is an axial section of a lighting projectile according to the invention;

Figure 2 is a view in perspective of the component parts of the stamping enclosing the parachute and the flare slab at the moment when they are breaking apart (when ejection occurs);

Figure 3 is an end view from the rear;

Figure 4 is a section through 4—4 (Fig. 1);
 Figure 5 is a partial view, in elevation, of the tail;

Figure 6 shows the flare slab suspended from its parachute after ejection.

According to the example shown, the body of the projectile comprises a central cylindrical portion 1 which is extended rearwards by a tapering base piece 2, with thicker walls, and which terminates in a cylindrical appendage 3 appreciably smaller in diameter than the calibre.

The front of body 1 is closed by an ogival cover 4 screwed or otherwise secured to body 1 at point 5, the attachment being contrived so as to collapse under the effect of the deflagration of the ejecting charge.

The body of the projectile contains, from front to rear: parachute 6 attached by a cable 7 to flare slab 8 which is provided at its lower end with an igniting charge 9 capable of being ignited by ejecting charge 10.

The parachute and the flare slab are housed inside a stamping 11, open at the rear and constituted by several juxtaposed members (Fig. 2). A spring 12, bearing against the bottom of cover 4, tends to drive the stamping and its contents out of the cover immediately ejection occurs. Stamping 11 rests against the rear edge of cover 4 by means of a bulge 13.

Ejecting charge 10 is housed within a recess contrived in a plate 14, which serves as a rear support for flare slab 8, and which itself bears against a shoulder 15 of the body of the projectile. Said plate is integral with a rod 16 positioned concentric with the axis of the projectile and perforated by several longitudinal channels enclosing delay action compounds 17 the durations of combustion of which are different. Each one of said channels opens out eccentrically, at the rear of rod 16, and is provided with a primer 18.

In appendage 3, which forms the base of the projectile, is rotatably mounted a tubular tail 19, open at the rear and comprising, in known manner, lateral perforations 20. Said tail receives a propelling cartridge 21 which engages therein with a certain amount of friction. The bottom of tail 19 is drilled with a longitudinal channel, out of centre, in which is positioned a small rod 22 acting as a selective firing pin for primers 18 and intended to be driven against any one of said primers under the effect of the deflagration of the gases of the cartridge. Until the shot is fired, firing rod 22 is held in the safety position by a disk 23 the resistance of which is calculated in such a manner that it can only be pierced by

the effect of a pressure of the order of magnitude of that brought into action at the time the shot is fired.

At its rear end, tail 19 is provided with stabilizing fins 24 the front edge of which is preferably incurved on the inner side to provide a notch as shown at point 25 (Fig. 1) in order to secure additional charges 26 which engage, on the other hand, under a flanged sleeve 27, directed outwards and towards the rear, which is placed on tail 19 in front of fins 24. Additional charges 26 are generally enclosed in combustible cartridge-bags the base of which is Celluloid or some other similar substance sufficiently plastic to lend itself to their adaptation on the tail in the manner shown.

The sleeve 27 comprises an inwardly curved tab 27a intended to engage with slots provided in appendage 3.

The angular position of the tail with respect to appendage 3 is indicated by means of figures such as II engraved on said appendage, with which the tab is made to register according to the duration of the delay action desired before ejection (Fig. 5).

According to the angular position given to the tail, firing rod 22 will strike a selected one of primers 18 when the shot is fired and, through delay action devices 17, will cause the ignition of ejecting charge 10 on the expiration of the period of time desired. Said charge drives out cover 4 together with stamping 11 and its contents substantially concentric with the axis of the projectile, the cylindrical portion of which acts as a gun barrel. Spring 12 then pushes the stamping away from the cover; and the flare slab 8, dropping owing to the force of gravity, withdraws parachute 6 from stamping 11 the component parts of which fall apart as shown in Figure 2. The flare slab, ignited by ejecting charge 10 and suspended from the parachute which opens out, burns and produces the desired illumination (Fig. 6).

The flare slab may, of course, be of any sort whatsoever and produce white or coloured light, and it might contain signal stars in case of need, etc.

It is to be understood that the present invention has only been illustrated and described as an example and that various modifications might be made to it without exceeding its scope.

I claim:

1. A projectile comprising a hollow structure including a body and a tail connected thereto for relative rotation about the axis of said structure; a flare slab and a suspension parachute therefor located in said body, an ejecting charge positioned in the body for ejecting the flare slab and parachute; a plurality of igniting units for the ejecting charge and having individually different delay periods and positioned in said hollow structure and having individual primers, each of said igniting units being capable upon deflagration of igniting the ejecting charge; a pressure-actuated firing pin carried by said hollow structure and selectively presented, in accordance with the prevailing relative angular position of the body and tail, in position for exciting the primer of the selected igniting unit upon the exertion of the gas pressure for propelling the projectile, whereby to determine the time of expulsion and ignition of the flare slab and parachute, and means for preventing the selecting device from exciting any of the primers except upon the exertion of said gas pressure.

2. A projectile comprising a hollow structure including a body and a tail connected thereto for relative rotation about the axis of said structure; a flare slab and a suspension parachute therefor located in said body, an ejecting charge positioned in the body for ejecting the flare slab and parachute; a plurality of igniting units for the ejecting charge and having individually different delay periods and positioned in said body and having individual primers located eccentric to said axis, each of said igniting units being capable upon deflagration of igniting the ejecting charge; said tail having a cavity, a propelling charge in said cavity, and a firing pin eccentrically carried by said tail and selectively presented, in accordance with the prevailing relative angular position of the body and tail, in position with one end opposite the primer of the selected igniting unit and with the other end exposed to the pressure in said cavity whereby the firing pin ignites the said selected primer upon deflagration of the cartridge for the propulsion of the projectile, whereby to determine the time of expulsion and ignition of the flare slab and parachute, and a safety disk located between the firing pin and the primers, of strength to resist piercing except under the action of a pressure upon the firing pin of the order of magnitude of that set up by deflagration of the cartridge.

3. A projectile comprising a hollow structure including a body and a tail connected thereto for relative rotation about the axis of said structure; a flare slab and a suspension parachute therefor located in the front of said body, an ejecting charge positioned in the body for ejecting the flare slab and parachute; a plurality of igniting units for the ejecting charge and having individually different delay periods and positioned in said body and having individual primers located eccentric to said axis, each of said igniting units being capable upon deflagration of igniting the ejecting charge; and a firing pin eccentrically carried by said tail and selectively presented, in accordance with the prevailing relative angular position of the body and tail, in position for exciting the primer of the selected igniting unit upon the propulsion of the projectile, whereby to determine the time of expulsion and ignition of the flare slab and parachute; a sleeve embracing the forward end of the tail and having a detent engageable with the body for indicating and fixing the relative position of rotation of the body and tail.

4. A projectile comprising a hollow structure including a body and a tail connected thereto for relative rotation about the axis of said structure; a flare slab and a suspension parachute therefor located in the front of said body, an ejecting charge positioned in the body for ejecting the flare slab and parachute; a plurality of igniting units for the ejecting charge and having individually different delay periods and positioned in said body and having individual primers located eccentric to said axis, each of said igniting units being capable upon deflagration of igniting the ejecting charge; and a firing pin eccentrically carried by said tail and selectively presented, in accordance with the prevailing relative angular position of the body and tail, in position for exciting the primer of the selected igniting unit upon the propulsion of the projectile, whereby to determine the time of expulsion and ignition of the flare slab and parachute; a sleeve embracing the forward end of the tail and having a detent engageable with the body for indicating and

fixing the relative position of rotation of the body and tail, and also having a flange at its rear end for engaging propelling charges for the projectile.

5. A projectile of smooth-bore mortar type comprising a body and a tail connected thereto for relative rotation about a common axis; stabilizing fins on the tail, one of said fins having a notch on its front edge; delay action timing means selectively energizable at different rela-

tive positions of rotation of the body and tail; a sleeve embracing the body and tail and connected to said tail and having a detent for engaging the body for fixing the relative rotated position of the body and tail, said sleeve also having a flange positioned opposite the notch for cooperation therewith for retaining a propelling charge for the projectile.

10
